UNITED STATES PATENT OFFICE

103,536

DESIGN FOR A COMBINED TRAFFIC OFFICER'S SAFETY BOOTH AND TRAFFIC SIGNAL

Elliott E. Loving, Memphis, Tenn., assignor to
National Safety Control Co., a corporation of
Tennessee

Application July 23, 1936, Serial No. 64,008

Term of patent 14 years

To all whom it may concern:

Be it known that I, Elliott E. Loving, a citizen of the United States, residing in Memphis, in the county of Shelby and State of Tennessee, have invented a new, original, and ornamental Design for a Combined Traffic Officer's Safety Booth and Traffic Signal, of which the following is a specification, reference being had to the accompanying drawing, forming part thereof, in which:

Figure 1 is a perspective view of the combined traffic officer's safety booth and traffic signal, showing my new design; and

Figure 2 is a perspective view of the opposite sides thereof.

I claim:

The ornamental design for a combined traffic officer's safety booth and traffic signal, as shown.

ELLIOTT E. LOVING.
